PIPE HOLDER OR SIMILAR ARTICLE

Max M. Schulte, 672 Springfield Ave., Newark, N.J.

Filed Jan. 19, 1960, Ser. No. 59,188

Term of patent 14 years

(Cl. D85—8)

I claim:

The ornamental design for a pipe holder or similar article, substantially as shown.
